PERMANENT HAIR WAVE INDICATOR

Finn H. Gulliksen, Pittsburgh, Pa., assignor to Westinghouse Electric & Manufacturing Company, East Pittsburgh, Pa., a corporation of Pennsylvania

Application March 28, 1939, Serial No. 264,673

19 Claims. (Cl. 219—24)

My invention relates to electric discharge apparatus for use in producing a permanent wave or a curl in hair or the like.

While dry hair is an insulator, hair which is being waved or curled is saturated with an ammonia solution and is therefore conductive. During the waving process cellular reorientation of the hair takes place, and this manifests itself as a variation in the electrical resistance of the hair. The form of the hair is dependent on its cellular structure and therefore the character of the wave or curl ultimately produced in the hair is a function of the resistance of the hair at the instant when the heating is interrupted. Accordingly, by controlling the flow of heat to the hair in accordance with the resistance of the hair, a wave of any desired type may be produced.

As is well known, hair-waving establishments are frequented principally by persons of the feminine sex. Such persons are not only fastidious as regards their personal appearance, and in particular, their hair, but at times are also somewhat capricious. To satisfy clients of this type and to, as far as possible, avoid the consequences of their caprice, it is essential that the utmost care be taken in complying with their expressed or even unexpressed desires. When a hair waving treatment is completed, the hair, and even the owner of the hair must look precisely as she wants to look. Irregularities such as may result if one wave is loose and another is tight may have disastrous consequences. For this reason, an arrangement for controlling the heat supplied for waving purposes must operate with the utmost precision and the final result must be fully predictable.

To complicate the problem of controlling the heat supplied for waving, the texture and composition of the hair of members of the fair sex varies over an extensive range. There are those whom nature has endowed as distinct blondes, brunettes, brownettes and red heads, but by far the greater proportion of their sisters fall by degrees between any two of these categories. In many cases, those dissatisfied with nature's gift introduce changes to suit themselves. Hair which has passed through an irreversible chemical reaction so that its color and composition is changed, is referred to as having been "touched up." This expression is an understatement.

It is apparent that under the circumstances, the owner of a hair waving establishment finds his position no "bed of roses." The resistance of hair which is determinative in hair waving varies widely, not only from person to person, but for the same individual. A person whose hair has, say, a high electrical resistance one week, because she happens to be blonde, may, the next week, in effect, short-circuit the con-

trol equipment, because she has, during the week, become dissatisfied with the color of her hair and has changed it. While the wave produced is substantially dependent on the relative change in resistance rather than the absolute resistance values, changes in the texture of hair do introduce difficulties. Hence, any arrangement designed to be used for varying the heating of hair in accordance with electrical resistance, or even the relative change in electrical resistance, to produce a wave or a curl, must eliminate the variables introduced by changes in the hair.

It is accordingly an object of my invention to provide an arrangement, functioning in dependence on the resistance of hair to be waved or curled, to control the supply of heat to the hair, that shall produce the precise wave desired.

Another object of my invention is to provide an arrangement for controlling the supply of heat to hair that is to be waved, that shall function in a precisely predictable manner.

A further object of my invention is to provide an arrangement for use in supplying heat to produce a wave or a curl in hair that shall operate to produce a desired wave independently of variations in the electrical resistance of the hair.

Still another object of my invention is to provide a hair waving control arrangement, by the operation of which the uniform waves or curls shall be produced in the hair treated.

An ancillary object of my invention is to provide an arrangement that shall respond to a potential, which varies as a function of time and may assume the same value at different instants, to operate in a predetermined manner after the potential has attained the said value a predetermined number of times.

Another ancillary object of my invention is to provide an arrangement, responsive to a potential which decreases to a minimum and then increases, that shall operate in a predetermined manner when the potential has increased to a predetermined value.

More concisely stated, it is an object of my invention to provide a simple and inexpensive system for controlling the heat supplied to hair being waved or curled that shall function with precision and that shall produce completely predictable results.

When hair is heated the resistance of the hair expressed in terms of the heating time is a function which has a minimum at a finite heating temperature. The instantaneous values of the function are determinative for the production of a curl or a wave in hair. However, the values of the function having any significance do not lie along its falling branch but

along its rising branch. Since the hair passes through the significant resistance-values along the falling branch of the resistance-time function before it attains the values along the rising branch of the curve, the principal problem involved in my invention is to prevent the operation of the controlling apparatus in a hair treating system until the significant resistance values are reached for the second time.

According to my invention, the supply of heat to hair is controlled by an electric discharge valve, preferably, but not necessarily, of the arc-like type. In the control circuit of the valve a capacitor and a resistor are provided. The capacitor and resistor are connected in an auxiliary circuit in which an asymmetrically conductive device such as an electric discharge rectifier or a dry rectifier is interposed. Current may, therefore, flow between the capacitor and the resistor in one sense only, and when the capacitor attains a predetermined potential by reason of current flow through the resistor, in one sense, a change in the capacitor potential is prevented by the asymmetric device. A potential which depends on the resistance of the hair is impressed across the resistor.

While the resistance of hair is decreasing during the heating process, the potential of the capacitor is changed by charge or discharge through the asymmetric device and the change is counteracted by the potential impressed on the resistor. After the hair resistance has passed through the minimum the counteracting effect of the potential dependent on the hair resistance is reversed and at the same time capacitor potential is prevented from change by the asymmetric device. When the hair now increases to the significant resistance, the corresponding potential produces a change in the conductivity of the valve and causes the control equipment to operate.

Variations in the resistance of the hair are prevented from materially influencing the character of the wave produced, in accordance with another aspect of my invention, by so arranging the capacitor and resistor circuit that the counteracting potentials impressed on the resistor increases and decreases in direct proportion to the hair resistance. This object is accomplished by charging the capacitor before the treating operation. During the treating operation the capacitor is discharged and a potential, proportional to the hair resistance, is impressed across the resistor in such manner that its polarity is opposite to the polarity of the capacitor potential and counteracts the effect of the discharge. When the hair attains its minimum resistance, the capacitor attains its minimum potential. As the potential proportional to the hair resistance now increases, it becomes effective to operate the control arrangement, because the capacitor is prevented by the asymmetric device from having compensating effect.

The novel features that I consider characteristic of my invention are set forth with particularity in the appended claims. The invention itself, however, both as to its organization and its method of operation, together with additional objects and advantages thereof, will best be understood from the following description of specific embodiments when read in connection with the accompanying drawings in which:

Figure 1 is a graph illustrating how the resistance of hair varies as a function of heating time,

Fig. 2 is a diagrammatic view showing an embodiment of my invention; and

Fig. 3 is a diagrammatic view showing a modification of my invention.

5 In Figure 1, the resistance of the hair is plotted vertically in ohms; heating time is plotted horizontally in arbitrary units. Two curves 5 and 7 to represent the hair resistance of two different people, or possibly of one person at different 10 times are reproduced. As can be seen from the curves, the hair resistance decreases from a value of the order of a thousand ohms to several hundred ohms or even less, and then increases. My invention depends upon the realization that the 15 character of the wave or curl produced is determined by the electrical resistance of the hair at the instant when the heating is interrupted. As indicated, three points marked L, M, and T may be selected to correspond to a loose wave, a 20 medium wave, and a tight wave. Since the hair resistance significant for a hair wave of any type, exists at two different times and the control apparatus must be operated when it appears the second time, the principal problem involved is 25 to provide a control system which shall fail to respond when the resistance value appears the first time, but shall respond when it appears the second time.

This object may be accomplished with a system such as is shown in Fig. 2. The hair 9 is saturated with an ammonia solution, secured near the scalp in clamps 10 and wound in a number of conductive tubes 11. When the hair is wound on the tube 11, a ribbon 12 of conductive foil is disposed along it in intimate contact with it and is also wound about the tube 11. The tube 11 is secured to the bracket of the clamp 12 and insulated therefrom and is covered with a water-saturated cloth (not shown for purposes of clarity). An electrical heater 13 is disposed over the tube 11 and the hair. The heater 13 is energized from a secondary section 14 of the supply transformer 15. The tube 11 and the foil 12 are connected across the terminals of a secondary section 17 of the transformer 15, through a full wave rectifier 19. The direct current terminals of the rectifier 19 are connected to the saturating winding 21 of a saturable reactor 23 and the impedance of the reactor is thus varied in accordance with the resistance of the hair 9.

The alternating current windings 25 of the reactor 23 are connected across another secondary section 27 of the transformer 17, through 55 the primary 29 of an auxiliary transformer 31. The secondary 33 of the latter transformer charges an auxiliary capacitor 35 through a second full-wave rectifier 37. The capacitor 35 is connected in the control circuit of a discharge 60 valve 39 of the high vacuum type and controls the flow of current between the anode 41 and cathode 43 of the valve. Initially, the resistance of the hair is relatively high and impedance of the reactor 23 is correspondingly large and the charge on the capacitor 35 is small. As the heating progresses, the reactor impedance decreases as the hair resistance decreases, and the charge impressed on the capacitor increases. The capacitor 35 is so connected in the control 65 circuit of the high vacuum valve 39 that, as its potential increases, the current flow through the valve increases.

The valve 39 is connected in a circuit which extends from the positive terminal 43 of a voltage divider 47 supplying direct current through

an auxiliary voltage divider 49, the anode 41 and cathode 43 of the high vacuum valve 39, to an intermediate tap 51 of the main voltage divider. The capacitor 35 is connected between the negative terminal 53 of the voltage divider 47 and the control electrode 55 of the valve 39 and the potential, dependent on the hair resistance which is impressed on it, counteracts the bias potential provided by the voltage divider.

The auxiliary voltage divider 49 is connected in a series circuit including a pair of capacitors 57 and 59 and a rectifier 61 preferably of the high vacuum type. The potential drop across the latter voltage divider 49 produced by the current flow through the high vacuum valve 39 is such that the capacitors 57 and 59 are charged through the rectifier 61. The adjustable tap 63 of the auxiliary voltage divider 49 is connected to the cathode 65 of an arc like valve 67 through a portion of a second voltage divider 69 which serves to supply a direct current bias potential to the arc-like valve 67. The control electrode 71 of the arc-like valve is connected intermediate the two capacitors 57 and 59 and the anode 73 of the arc-like valve is connected to the positive terminal 75 of the second voltage divider 69 through the exciting coil 77 of a relay 79 and the upper contact 81 of a reset switch 83.

Initially the bias provided by the second voltage divider 69 maintains the arc-like valve 67 non-conductive. The charge impressed on the capacitors 57 and 59 by reason of the potential impressed across the auxiliary divider 49 is in such a sense as to counteract the bias potential. However, as the current flow through the high vacuum valve 39 increases by reason of the decrease in the resistance of the hair 9, the effect of the capacitor potential is counteracted by the potential drop across the auxiliary voltage divider 49 in series with the high vacuum valve 39 and the arc-like valve 67 remains non-conductive. When the hair resistance attains its minimum value, the capacitors 57 and 59 reach their maximum potential. After this the current flow through the voltage divider 49 and the high vacuum valve 39 decreases and the potential drop across the voltage divider becomes smaller than the potential of the capacitors. The discharge of the capacitors 57 and 59 into the auxiliary divider 49 is, however, prevented by the rectifier 61 and, therefore, the capacitor potential for minimum hair resistance remains impressed in the control circuit of the arc-like valve 67 while the potential drop across the voltage divider by which it was originally counteracted, continues to decrease. At a point predetermined by the setting of the adjustable tap 63 of the auxiliary voltage divider 49, the critical control potential of the arc-like valve 67 is exceeded and the latter is rendered conductive.

The relay 79 is now operated and actuates its contactor 85 to open the supply circuit 87 of the heater 13. As a result the heating of the hair 9 is interrupted. The setting of the tap 63 of the voltage divider 49 is such that the interrupter corresponds to one or the other of the points L, M or T on a curve, such as 5 or 1, corresponding to the hair. When the hair 9 is removed from the container 13, it therefore has the desired wave. The arrangement can be reset by operating the switch 83. The resetting operation may be accomplished by momentarily actuating switch 83 to close the lower contact members and to open upper contact members 81 and then re-

storing the contact members of switch 83 to their original condition as shown in Fig. 2. The closing of the lower contact members of switch 83 completes a circuit for discharging capacitors 57 and 59. The opening of contact members 81 de-energizes valve 67 and coil 77 of relay 79, thereby reclosing contact members 85 to reclose the supply circuit 87 of heater 13 and to initiate the next cycle of operation similar to that hereinbefore explained. Coil 77 remains deenergized at the beginning of the cycle of operation when contact members 81 are reclosed because of the deionization of valve 67.

The operation of the apparatus disclosed in Fig. 2 may, of course, be made dependent on the absolute resistance of the hair. For this purpose a set of characteristic curves for different initial hair resistances may be provided with each waving machine and the setting for any client determined from the curve after the initial resistance of the hair has been measured. However, it has been found that the characteristics of a wave depends on the ratio of the hair resistance at which the heating is interrupted to the minimum resistance and this principle may be applied to facilitate the operation.

In the apparatus disclosed in Fig. 2, difficulties are involved in properly setting the apparatus because the potential on which the operation of the control equipment is dependent varies in the opposite sense to the resistance of the hair 9. The high vacuum valve 39 is operated along the linear portion of its characteristic and therefore the potential impressed across the auxiliary voltage divider 49 is proportional to the potential impressed on the capacitor 35. For proper operation the latter potential must vary in direct proportion to the reciprocal of the hair resistance. Unless this relationship is maintained, the ratio of the hair resistance at which the operation takes place to the minimum resistance is different for any setting of the divider 49 and for different initial or minimum hair resistances. The hyperbolic relationship between potential and hair resistance which is necessary for proper operation is sometimes difficult to obtain, and for this reason, I have provided the arrangement shown in Fig. 3 in which it is not necessary.

In this case the hair resistance 89 shown symbolically is interposed between the control electrode 91 of a high vacuum valve 93 and one terminal of the secondary 95 of an auxiliary transformer 97 supplied from an alternating current source 99 which may be of the usual 60-cycle type. The cathode 101 of the high vacuum valve 93 is connected to the intermediate tap 103 of the secondary 95. The remaining terminal of the secondary 95 is connected through a resistor 105 to the junction point of the hair resistance 89 and the conductor from the control electrode 91. The resistor 105 may, for the purpose of the present explanation, be assumed to have the magnitude of the initial hair resistance. However, it may, and often does, have a magnitude equal to the average hair resistance or any other magnitude within the range through which the hair resistance varies. I have used a resistor 105 having a resistance of 500 ohms. This resistance corresponds to a hair resistance range from 100 to 1200 ohms. The common connection point of the intermediate tap 103 and the cathode 101 is also connected to the junction point 107 of two networks 109 and 111. Each of the networks 109 and 111 consists of a resistor 113 shunted by a capacitor 115. The termi-

nals 117 of the networks 109 and 111 that are not connected together are connected, respectively, to opposite polarity terminals of corresponding secondary sections 119 and 121 of the main supply transformer 123. The remaining terminals of the secondary sections 119 and 121 are connected to the anodes 125 of a full-wave rectifier tube 127. The cathode 128 of the rectifier 127 is connected to the anode 131 of the high vacuum valve 93. Since the secondary sections 119 and 121 are connected with their opposite polarity terminals to the networks 109 and 111 and to the anodes 125, current is conducted during alternate half periods of the source through each of the resistors 113 in the networks, and the capacitors 115 are correspondingly charged.

The hair resistance 89 is connected in a balanced network of which it forms one arm, the resistor 105 in series with it forms the other arm, and the remaining arms are constituted by the sections of the secondary 95 of the auxiliary transformer 97 extending from the intermediate tap 103. The cathode 101 of the high vacuum valve 93 and the control electrode 91 are at conjugate points of the network and the potential drop between the control electrode 91 and the cathode 101 is, therefore, dependent on the degree of balance of the network.

Initially, when the hair is cold, the network is substantially balanced and the potential between the control electrode 91 and the cathode 101 is zero. At this time, the current flow through the resistors 113 in series with the rectifier 127 during the alternate half-periods is equal, and the capacitors 115 are charged to substantially the same potentials. As the hair resistance 89 decreases, an increasing alternating potential is impressed between the control electrode 91 and the cathode 101. The current flow through one of the series resistors 113 is, therefore, correspondingly increased while the current flow through the other is correspondingly decreased. The parallel capacitors 115 are, therefore, charged to increasingly different potentials.

The potential drop across the two capacitors 115 is impressed on another capacitor 133 which is connected across the unconnected terminals 117 of the networks 109 and 111. The latter capacitor is connected between the control electrode 135 and the cathode 137 of a second high vacuum valve 139 through resistors 141 and 143, respectively. Another capacitor 145 is connected directly between the control electrode 135 and the cathode 137.

The high vacuum valve 139 is supplied with direct current anode-cathode potential derived from the main source 99 through a rectifier system 147. The negative terminal 149 of the direct current supply is connected to the junction point 151 of the capacitor 133 and the resistor 143 in series with the cathode 137. The positive terminal 153 of the supply 147 is connected to the anode 155 of the high vacuum valve 139 through a voltage divider 157 and a resistor 159. The connection of the capacitors 133 and 145 to the networks 109 and 111 in the hair resistance circuit is such that the potential impressed between the control electrode 135 and the cathode 137 of the valve 139 is directly proportional to the hair resistance. The valve 139 is operated along the linear portion of its characteristic and, therefore, the current flow through the resistor 159 and the voltage divider 157 in series with the valve and the potential drop across

these elements varies in substantially direct proportion with the hair resistance.

Across the resistor 159 and the voltage divider 157, a capacitor 161 is connected in series with a rectifier 163. The capacitor 161 is connected in the control circuit of an arc-like valve 165 through which the relay 167 controlling the heat supply to the hair is energized. The control circuit extends from the upper terminal of the capacitor 161 through a conductor 169, a biasing capacitor 171, a conductor 173, the cathode 175 of the arc-like valve, the control electrode 177 of the valve, the adjustable tap 179 of the voltage divider 157, the resistor 159 in series with the voltage divider, to the lower terminal of the capacitor.

Before the treating operation, the capacitor 161 is maintained charged in a circuit which extends from the positive terminal 153 of the direct current supply 147 through the upper contact 181 of a circuit controller 183, which may be a push-button or a foot switch, the capacitor 161, the lower contact 185 of the circuit controller, to the negative terminal 149 of the supply. When the treatment is initiated, the foot switch is operated and the charging circuit for the capacitor 161 is opened. The capacitor potential is initially substantially equal to the potential drop across the direct current supply 147. The potential impressed across the high vacuum valve 139 and the two series impedances 157 and 159 is also substantially equal to that of the direct current supply. The potential impressed across the resistor 159 and the voltage divider 157 is, therefore, equal to the initial capacitor potential minus the drop across the high vacuum valve 139. The rectifier 163 is so connected in series with the capacitor 161 and the voltage divider 157 that current may flow from the capacitor, through the voltage divider 157 and the resistor 159 when the capacitor potential is larger than the potential across the voltage divider and resistance. Initially, therefore, the capacitor potential automatically adjusts itself to correspond to the potential drop across the voltage divider and the resistor.

The plate of the capacitor which is connected to the cathode 175 of the arc-like valve 165 is positive and the other plate is negative. The capacitor potential, therefore, tends to maintain the valve 165 non-conductive when the switch 183 is first operated. As the treatment progresses the current flow through the high vacuum valve 139 decreases by reason of the decrease in the hair resistance 89, the potential drop across the voltage divider 157 and resistor 159 decreases and the capacitor 161 continues to discharge through the two elements. However, the decrease in potential of the capacitor 161 has no effect on the arc-like valve 165 as it is counteracted by the potential drop arising from the current flow through the resistance 159 and the voltage divider 157.

After the hair attains the minimum resistance, the potential across the voltage divider 157 and resistor 159 increases. At this point the potential impressed on the capacitor 161 is a minimum and the rectifier 163 in series with the capacitor prevents the latter from being recharged by reason of the potential drop across the resistance 159 and the divider 157. As a result, the positive potential impressed between the control electrode 177 and the cathode 175 of the arc-like valve 165 gradually increases by reason of the increasing current flow through the high vacuum valve 139. The critical potential of the valve is

exceeded at a value of hair resistance corresponding to the setting of the adjustable tap 179 of the voltage divider. At this point the supply of current to heat the hair is discontinued. Since potential across the resistor 158 and voltage divider 157 is in this case proportional to the hair resistances, the ratio of the hair resistance at the point of operation to the minimum hair resistance for any setting of the tap 179 is independent of the absolute hair resistance.

Although I have shown and described certain specific embodiments of my invention, I am fully aware that many modifications thereof are possible. My invention, therefore, is not to be restricted except in so far as is necessitated by the prior art and by the spirit of the appended claims.

I claim as my invention:

1. For use in the heating of hair or the like from a source of current to produce a wave or curl of a predetermined character therein the combination comprising a circuit for supplying said hair with current from said source, electric discharge valve means for controlling the magnitude of the current flow through said circuit and means responsive to the electrical resistance of said hair for controlling said valve means.

2. For use in the heating of hair or the like from a source of current to produce a wave or curl of a predetermined character therein the combination comprising a circuit for supplying said hair with current from said source, means for controlling the magnitude of the current flow through said circuit and means responsive to the electrical resistance of said hair for controlling said valve means, said responsive means including a saturable reactor having a saturating winding supplied with current which varies in accordance with the resistance of the hair.

3. For use in the heating of hair or the like from a source of current to produce a wave or curl of a predetermined character the combination comprising a circuit for supplying said hair with current from said source, an electric discharge valve having a control circuit for controlling the magnitude of the current flow through said circuit, means for impressing a potential in said control circuit which responds to the minimum resistance of the hair, and means functioning to counteract said potential until said hair attains a predetermined resistance greater than the minimum.

4. For use in the heating of hair or the like from a source of current to produce a wave or curl of a predetermined character the combination comprising a circuit for supplying said hair with current from said source, an electric discharge valve having a control circuit for controlling the magnitude of the current flow through said circuit, a capacitor and resistor in said control circuit, means for charging said capacitor in response to the resistance of said hair and in such a sense that the potential on said capacitor tending to render said valve conductive increases as the reactance of the hair decreases, said charging means including said resistor and means for preventing the discharge of said capacitor, said resistor being so connected that the potential drop across it during the charging counteracts the effect of said capacitor potential on said valve.

5. In combination, an electric discharge valve having a control electrode and a principal electrode, a network including charge storing means, a resistor and asymmetric conductive means in-

terposed between said resistor and said charge storing means, means for connecting said charge-storing means to one of said electrodes, means for connecting said resistor to the other of said electrodes and means for supplying current of varying magnitude through said resistor.

6. In combination, an electric discharge valve having a control electrode and a principal electrode, a network including charge storing means, a resistor and asymmetric conductive means interposed between said resistor and said charge storing means, means for connecting said charge storing means to one of said electrodes, means for connecting said resistor to the other of said electrodes and means for supplying current the magnitude of which decreases to a predetermined minimum value and then increases from said minimum value through said resistor.

7. For use in supplying current from a source to heat a material the resistance of which varies in magnitude as a function of the heating time from a predetermined value to a minimum and then to a second value higher than said minimum, the combination comprising a circuit for supplying said material from said source, electric discharge valve means for controlling the magnitude of the current flow through said circuit and means responsive to the resistance of said material for controlling said electric discharge valve means.

8. For use in supplying current from a source to heat a material the resistance of which varies in magnitude as a function of the heating time from a predetermined value to a minimum and then to a second value higher than said minimum, the combination comprising a circuit for supplying said material from said source, electric discharge valve means of the arc-like type for controlling the closing and opening of said circuit and means responsive to the resistance of said material for controlling said electric discharge valve means.

9. In combination an electric discharge valve having a control electrode and a principal electrode, a capacitor, a discharge circuit for said capacitor including an impedance and an asymmetrically conductive device, means for connecting said circuit and said capacitor between said control electrode and said principal electrode, means for charging said capacitor to a potential such that said valve is initially non-conductive, and means for impressing a potential across said impedance which decreases from a value at most equal to that of the potential to which said capacitor is charged to a minimum value and then increases.

10. In combination an electric discharge valve having a control electrode and a principal electrode, charge storing means, a discharge circuit for said charge storing means including an impedance and an asymmetrically conductive device, that permits said charge storing means to discharge when the potential across said charge storing means is greater than the potential across said impedance, means for connecting said circuit and said charge storing means between said control electrode and said principal electrode, means for charging said charge-storing means to a potential such that said valve is initially non-conductive, and means for impressing a potential across said impedance which decreases from a value at most equal to that of the potential to which said charge storing means is charged to a minimum value and then increases.

11. In combination an electric discharge valve

having a control electrode and a principal electrode, charge-storing means, means for charging said charge-storing means, a resistor and an asymmetrically conductive device so connected to said charge-storing means that it can discharge through said resistor, means for connecting said charge-storing means and said resistor in circuit with said control electrode and principal electrode in such manner that said charge-storing means when charged maintains said valve non-conductive and means for impressing a potential across said resistor, while said charge-storing means is discharging, which is of opposite polarity in the resistor-charge-storing means circuit to the potential of said charge-storing means and which varies from a value at most equal to the initial potential on said charge-storing means to a minimum value and then increases to a value such that said valve is rendered conductive.

12. In combination an electric discharge valve having a control electrode and a principal electrode, charge-storing means, means for charging said charge-storing means, a resistor and an asymmetrically conductive device so connected to said charge-storing means that it can discharge through said resistor, means for connecting said charge-storing means and said resistor in circuit with said control electrode and principal electrode in such manner that said charge-storing means when charged maintains said valve non-conductive and means for impressing a varying potential across said resistor, while said charge-storing means is discharging.

13. For use with an element the impedance of which, when expressed in terms of time over a predetermined interval, is a function which has a minimum at a finite time point in said interval, the combination comprising an electric discharge valve having a control electrode and a principal electrode, charge-storing means, means for charging said charge-storing means, a resistor and an asymmetrically conductive device so connected to said charge-storing means that it can discharge through said resistor, means for connecting said charge-storing means and said resistor in circuit with said control electrode and principal electrode in such manner that said charge-storing means when charged maintains said valve non-conductive and means for impressing a potential across said resistor, while said charge-storing means is discharging, which is of opposite polarity in the resistor-charge-storing means circuit to the potential of said charge-storing means and which varies in the same sense as the impedance of said element varies during said interval.

14. In combination an electric discharge valve having a control electrode and a principal electrode, charge-storing means, means for charging said charge-storing means, a resistor and an asymmetrically conductive device so connected to said charge-storing means that it can discharge through said resistor, means for connecting said charge-storing means and said resistor in circuit with said control electrode and principal electrode and means for impressing a potential across said resistor, while said charge-storing means is discharging, which is of opposite polarity in the resistor-charge-storing means circuit to the potential of said charge-storing means

and which varies from a value at most equal to the initial potential on said charge-storing means to a minimum value and then increases to a value such that said valve is rendered conductive.

15. In combination an electric discharge valve having a control electrode and a principal electrode, charge-storing means, a discharge circuit for said charge-storing means including an impedance and an asymmetrically conductive device that permits said charge-storing means to discharge when the potential across said charge-storing means is greater than the potential across said impedance, means for connecting said circuit and said charge-storing means between said control electrode and said principal electrode, means for charging said charge-storing means to a predetermined potential and means for impressing a potential across said impedance which decreases from a value at most equal to that of the potential to which said charge-storing means is charged to a minimum value and then increases.

16. For use with an element the impedance of which, when expressed in terms of time over a predetermined interval, is a function which has a minimum at a finite time point in said interval, the combination comprising an electric discharge valve having a control electrode and a principal electrode, a capacitor, a discharge circuit for said capacitor including an impedance and an asymmetrically conductive device, means for connecting said circuit and said capacitor between said control electrode and said principal electrode, means for charging said capacitor to a predetermined potential and means for impressing a potential across said impedance which varies in the same manner as said impedance during said interval.

17. In combination, an electric discharge valve having a control electrode and a principal electrode, a network including charge-storing means, a resistor and asymmetric conductive means interposed between said resistor and said charge-storing means, means for connecting said charge-storing means to one of said electrodes, means for connecting said resistor to the other of said electrodes and means for supplying current the magnitude of which first varies in one sense and then in the opposite sense through said resistor.

18. For use in supplying current from a source to heat a material the resistance of which when expressed in terms of the heating time is a function which has a stationary point, the combination comprising a circuit for supplying said material from said source, electric discharge valve means for controlling the magnitude of the current flow through said circuit and means responsive to the resistance of said material for controlling said electric discharge valve means.

19. In combination, an electric discharge valve having a control electrode and a principal electrode, a network including a resistor, charge-storing means and asymmetric conductive means connected in series circuit relation across said resistor, means for connecting said charge-storing means to one of said electrodes, means for connecting said resistor to the other of said electrodes, and means for supplying current of varying magnitude connected across said resistor.
